(57) **CLAIM**

The ornamental design for a bracket for fixing communication equipment, as shown and described.

DESCRIPTION

FIG. 1 is a perspective view of a bracket for fixing communication equipment, showing our new design;

FIG. 2 is a front view thereof;

FIG. 3 is a rear view thereof;

FIG. 4 is a side view thereof;

FIG. 5 is another side view thereof;

FIG. 6 is a top view thereof; and,

FIG. 7 is a bottom view thereof.

The broken lines in the figures represent environmental subject matter and portions of the article which form no part of the claim.
